UNITED STATES PATENT OFFICE.

SAHATIEL G. MANDALIAN, OF NORTH ATTLEBORO, MASSACHUSETTS.

SUSPENSION-SLEEVE FOR MESH-MACHINES.

1,397,288.

Specification of Letters Patent.

Patented Nov. 15, 1921.

Application filed January 3, 1921. Serial No. 434,772.

To all whom it may concern:

Be it known that I, SAHATIEL G. MANDALIAN, a citizen of the United States, residing at North Attleboro, in the county of 5 Bristol and State of Massachusetts, have invented certain new and useful Improvements in Suspension-Sleeves for Mesh-Machines, of which the following is a specification.

10 My invention relates to a device adapted for use in a mesh machine for receiving the initial row of units previously formed, and for carrying said row of units during the attachment of subsequent rows of units in 15 such a manner as to produce a mesh. When a mesh machine has the initial units presented to it in a row arranged to receive subsequent rows thereon, the machine is sometimes called a mesh machine. Two 20 such machines and the mesh formed thereby are shown in U. S. Patents No. 948,615 issued February 8, 1910, to Pratt, and No. 1,139,799 issued to Pratt, March 18, 1915.

In such machines the operation was not 25 wholly automatic because a suspending or receiving device was lacking, and it was necessary to make by hand a long initial broad strip of flexible mesh fabric for suspension on the mandrel to present a row of 30 units to the forming tools. This strip had necessarily a more or less irregular and rough surface which prevented regular movement upon the suspension anvil, with consequent breakage and delay in machine operation.

35 The essential objects of my invention are to overcome the enumerated disadvantages attendant upon the absence of a suspension device, and provide a device which will enable mesh machines to operate wholly automatically.

To the above ends essentially my invention consists in such parts and in such combinations of parts as fall within the scope of the appended claims.

40 In the accompanying drawings which form a part of this specification—

Figure 1 is a plan view partially in section of the anvil and certain parts adjacent thereto of one usual form of mesh machine 45 in which my device is mounted,

Fig. 2, a vertical section of the same including a portion of two sets of ring forming tools,

Figs. 3 and 4, a side elevation and plan 50 respectively of the sleeve,

Fig. 5, a section on line 5—5 of Fig. 4,

Fig. 6, an enlarged fragmentary elevation of the margin of the sleeve with rings formed thereon,

Fig. 7, an enlarged bottom perspective of 60 a portion of the sleeve,

Fig. 8, a fragmentary vertical section of some links and of machine portions adjacent thereto,

Fig. 9, a diagrammatic plan of the anvil 65 and forming tools, and

Fig. 10, a diagrammatic side view of the same.

Like reference characters indicate like parts throughout the views. 70

In the drawings 11 represents the hollow post or mandrel of a usual mesh machine having the thread 12 upon its upper portion and carrying the reciprocating radially arranged dies 13. Two sets of forming tools 75 coöperating with the dies are shown, alike in all respects, and diametrically oppositely disposed. A description of one set serves for both. 15 is one of the guide blocks supporting the plunger 16 coöperating with the die 13 and carrying the reciprocating die rod 17 and sleeve 19 with its prongs 20. 21 is the transverse passage for the intermittently fed wire. The bell crank lever 23 carries the forming anvil 24 and is engaged 85 by the reciprocating plunger 25. 27 is the fixed supporting ring carrying loosely the sleeve 28 with its internal vertical ridges 29, and external ratchet teeth 30, engaged by pawl 32 pressed by spring 33 in rock shaft 90 34. The sleeve 28, which is advanced step by step by the pawl and shaft the distance of a tooth, is retained by the pawl 36. The ridges or thread 12 of the mandrel and the ridges or ribs 29 of the sleeve 28 coöperate 95 with the shallow depressions in the surfaces of the finally manufactured mesh sleeve located therebetween so that the rotation of the sleeve 28 will cause the mesh sleeve to move upwardly with itself on the mandrel 100 in a spiral path step by step in the usual manner. The sleeve 28 is depressed at each rotation by the contact of the roller 37 with the ring projection 38.

It is in conjunction with the described familiar mechanism that my novel device is herein illustrated, although such use is not exclusive.

My receiving or suspension device is purposed to be inserted between the mandrel 11 110 and the sleeve 28, when the latter is present, and in detail consists of a stiff sleeve or tube

39 of sheet metal provided with an internal spiral groove 40 adapted to loosely register with the spiral ridge or thread 12 of the mandrel 11. The exterior of the member 39 is provided around its circumference with a series of longitudinally disposed grooves 43 and ribs 44 adapted to slidably interengage the ridges 29 of the operating sleeve 28. The ribs 44 have preferably transversely inclined faces appearing in transverse section as if they were ratchet teeth. The lower portion of the sleeve 39, as at 45, is preferably smooth and of reduced thickness. The lower edge of the member 39 is preferably inclined at an angle corresponding with the incline of the spiral thread or groove 40 and is interrupted at diametrically opposite points by rounded vertical shoulders 46 and 47 forming two inclined edge sections 49 and 50. The number of these shoulders is determined by the number of sets of forming tools. In this case two sets of forming tools are supposed to be employed, and two rows of rings are being simultaneously attached. The shoulders are in depth about the radius of one of the rings of the mesh to be formed. Adjacent the edges of sections 49 and 50 respectively are series of equispaced holes 53 and 54. The portions 49 and 50 respectively of the sleeve 39 are preferably slightly outwardly and inwardly inclined respectively at their lower edges as shown at 57 and 58 in Fig. 7.

35 The rings are formed by the described forming tools in the usual manner. The two sets of tools are diagrammatically indicated in Figs. 9 and 19 by *a* and *b*, which respectively initially form and insert the rings 61 and 62 in the series of holes 53 and 54 and thereafter as the sleeve 39 revolves form continuous rows of intermeshing links, each spiral row having the links angularly disposed relatively to each other.

40 45 It will be observed that in this case the rings 62 depend within the sleeve 39, and the rings 61 depend exteriorly of the sleeve. The angular relation of the link rows is assisted by the inclines of the sleeve portions 49 and 50.

55 As the mesh formed on the device 39 grows in length the latter gradually moves upwardly upon the anvil until it is free therefrom whereupon the mesh is manually severed from the sleeve, and its place is taken by the mesh severed therefrom now in the machine.

I claim:—

60 1 In a mesh machine, a mandrel, a feeding sleeve rotatably mounted around the

mandrel, and a rigid suspension sleeve engaging the mandrel and the feeding sleeve.

2. In a mesh machine, a mandrel provided with a thread, a stiff suspension sleeve provided with a thread loosely engaging the first thread, and means for rotating the suspension sleeve. 65

3. In a mesh machine, a mandrel provided with a thread, a feeding sleeve rotatable around the mandrel provided with internal vertical grooves, and a rigid suspension sleeve provided with an internal thread loosely engaging the first thread, and external vertical ribs slidable in the grooves. 70

4. In a mesh machine, a mandrel provided with a thread, a suspension sleeve provided with a thread engaging the first thread, and vertically disposed transversely inclined ribs upon the exterior of the suspension sleeve. 75

5. In a mesh machine, the combination with a mandrel and feeding sleeve, of a stiff suspension sleeve loosely engaging the mandrel and the feeding sleeve and provided at its lower end with series of marginal holes. 80

6. In a mesh machine, a mandrel, a feeding sleeve, a stiff suspension sleeve engaging the mandrel and sleeve, and provided at its lower end with an inclined edge and 90 with an inclined series of marginal holes.

7. In a mesh machine, a mandrel, a stiff suspension sleeve mounted on the mandrel provided upon its lower edge with vertical shoulders and with the portions of the edge 95 intermediate the shoulders inclined, and provided with inclined series of marginal holes adjacent the inclined edge portions.

8. In a mesh machine, a mandrel, a stiff suspension sleeve loose on the mandrel provided upon its lower edge with depending shoulders and having the portions of the sleeve intermediate the shoulders laterally inclined inwardly and outwardly, said intermediate portions being also provided with 105 series of marginal holes.

9. As an article of manufacture, a suspension sleeve for ring mesh machines comprising a cylindrical body provided with a smooth lower portion and with an internal 110 thread above the smooth portion, vertical external ribs above the smooth portion, said smooth portion being provided with depending shoulders and inclined edge portions between the shoulders, and with series of marginal holes. 115

In testimony whereof I have affixed my signature.

SAHATIEL G. MANDALIAN.
